(57) **CLAIM**

We claim the design for a water filtration housing for water filtration cartridge, as shown and described.

DESCRIPTION

FIG. 1 is a perspective view from the top and the front of a water filtration housing for water filtration cartridge showing our new design;

FIG. 2 is a similar perspective view to FIG. 1 from the top and the back thereof;

FIG. 3 is a side elevation view thereof;

FIG. 4 is a back elevation view thereof; and,

FIG. 5 is an enlarged top plan view thereof.
